1,534,647

UNITED STATES PATENT OFFICE.

JACOB F. KEMMERLING, OF CLEVELAND HEIGHTS, OHIO.

ROOFING BRACKET.

Application filed October 10, 1923. Serial No. 667,628.

To all whom it may concern:

Be it known that I, JACOB F. KEMMERLING, a citizen of the United States, residing at Cleveland Heights, in the county of 5 Cuyahoga and State of Ohio, have invented a certain new and useful Improvement in Roofing Brackets, of which the following is a full, clear, and exact description, reference being had to the accompanying 10 drawings.

My invention relates to roofing brackets and more particularly is an improvement on the roofing bracket patented to William H. Boyd by Letters Patent of the United States 15 Number 1,127,173 granted February 2, 1915. In the drawings accompanying this specification and forming a part thereof I have shown, for purposes of illustration, one form which my invention may assume. In these 20 drawings:

Figure 1 represents my improved roofing bracket in position on a roof and in use,

Figure 2 is a detail view illustrating the 25 relation between the shoulder and the plank supporting member,

Figure 3 is a general view of the shoulder,

Figure 4 shows the action by which the shoulder is attached to the plank supporting 30 member, while

Figure 5 shows the action by which the shoulder is locked to that member.

The particular embodiment of my invention herein shown is adapted for use with a roofing bracket 11 which comprises a plate 35 12 adapted to lie against the roof 13 and secured in position upon the roof 13 by means of a strip 14 carried by the plate 12 in such manner that the complete removal of the strip 14 from the plate 12 is prevented and 40 provided with a plurality of notches 15 each adapted to embrace a projection, such as the nail 16 extending from the roof 13. Pivoted at the upper end of this plate 12 is a plank supporting member 17 the free end of which 45 is supported by means of a strut 18 pivoted to the member 17 and arranged to extend between the member 17 and the plate 12 and prevented from movement longitudinally of the plate 12 by its entrance into any one of 50 a plurality of pairs of slots 19 carried by flanges 20 formed from and integral with the plate 12. The structure so far described is substantially identical with that disclosed in said Patent 1,127,173.

55 It will be apparent that the device above described may be normally stored or trans-

ported with the strip 14 retracted and the member 17 and strut 18 folded against the plate 12 and that when it is desired to use the bracket the strip 14 is drawn out and hooked over a suitable nail 16 or other projection, the strut 18 and member 17 are raised away from the plate 12, and the lower end of the strut 18 is inserted into that pair of recesses 19 which will maintain the member 17 in a position ready to receive and support the plank 21.

Were all planks to be used of the same width the member 17 might be made of this width and the plank held against movement 70 away from the roof 13 by its engagement with the upper end of the strut 18. In actual practice, however, it is not advisable or practical to transport the planks from place to place but on the contrary it is desirable 75 to use planks which are to be used later for other purposes and it is therefore necessary to use whatever width of plank may be available. I therefore provide means effective to hold the plank in position against 80 the roof and adjustable to perform this result in connection with planks of various widths.

The means herein shown for this purpose comprises a frame 22 generally U-shaped 85 and provided at the ends of the U with a hook 23 arranged to be passed through any one of a plurality of pairs of apertures 24 provided in the member 17 while the frame 22 is in the horizontal position, as shown in 90 Figure 4, after which the frame 22 is raised to the vertical position, as shown in Figure 5, in which position it may be locked by means of a link 25 pivoted at one end to the horizontal portion of the frame 22 and provided at the other end with an angularly extending foot 26 which is adapted to engage the member 17 to force the frame 22 into fully elevated position with the hooks 23 tightly engaging the underside of the member 17 and which extends from the link 25 at that angle which will permit the link 25 to swing under the frame 22 slightly past the perpendicular position into an over-thrown position in which the link 25 and 100 frame 22 will form a toggle effective to normally prevent dislodgment of the link 25 and therefore effective to normally prevent removal of the frame 22 from the member 17. Under certain circumstances, however, 110 I may desire to additionally secure the link 25 in position and in such cases I may pro-

vide the foot 26 with an aperture 27 arranged to cooperate with any one of a plurality of apertures 28 formed in the member 17 to permit the passage through the aperture 27 and the corresponding aperture 28, when the link 25 is in its overthrow position, of any member suitable for preventing relative movement of the foot 26 and member 17, such, for example, as a nail.

From the above description it will be obvious that with the parts positioned as shown in Figures 1 and 2 the frame 22 will form a shoulder effective to hold the plank 21 in position against the roof 13 and adjustable to cooperate with planks of various widths.

A consideration of the particular form of my invention disclosed herein will suggest to those skilled in the art various changes and modifications which may be made without departing from the spirit of my invention or sacrificing the advantages thereof. It will be understood, however, that the disclosure herein is illustrative only and that my invention is not limited thereto but is intended to and does include all changed and modified constructions which lie within the spirit of my invention and are effective for the purpose for which my invention was primarily made.

I claim:

1. In combination with a roofing bracket having a plank supporting member arranged to receive a plurality of hooks, a shoulder for engaging the edge of such plank and comprising: a frame having hooks adapted to be received by said member when said frame is inclined to said member and to be locked to said member when said frame is perpendicular to said member; a link pivoted to said frame, cooperating with said member, and arranged to form with said frame an overthrow linkage adapted when set to hold said frame in such perpendicular position; and means for locking said link in holding position.

2. In combination with a roofing bracket having a plank supporting member arranged to receive a plurality of hooks, a shoulder for engaging the edge of such plank and comprising: a frame having hooks adapted to be received by said member when said frame is inclined to said member and to be locked to said member when said frame is perpendicular to said member; and a link pivoted to said frame, cooperating with said member, and arranged to form with said frame an overthrow linkage adapted when set to hold said frame in perpendicular position.

3. In combination with a roofing bracket having a plank supporting member arranged to receive a plurality of hooks, a shoulder for engaging the edge of such plank and comprising: a frame having hooks adapted

to be received by said member when said frame is inclined to said member and to be locked to said member when said frame is perpendicular to said member; holding means carried by said frame and arranged to cooperate with said member to hold said frame in such perpendicular position; and means for locking said holding means in holding position.

4. In combination with a roofing bracket having a plank supporting member arranged to receive a plurality of hooks, a shoulder for engaging the edge of such plank and comprising: a frame having hooks adapted to be received by said member when said frame is in one position and to be locked to said member when said frame is in another position; and a link pivoted to said frame, cooperating with said member, arranged to form with said frame an overthrow linkage adapted when set to hold said frame in such other position; and means for locking said link in holding position.

5. In combination with a roofing bracket having a plank supporting member arranged to receive a plurality of hooks, a shoulder for engaging the edge of such plank and comprising: a frame having hooks adapted to be received by said member when said frame is inclined to said member and to be locked to said member when said frame is perpendicular to said member; and means carried by said frame and arranged to cooperate with said member to hold said frame in such perpendicular position.

6. In combination with a roofing bracket having a plank supporting member arranged to receive a plurality of hooks, a shoulder for engaging the edge of such plank and comprising: a frame having hooks adapted to be received by said member when said frame is in one position and to be locked to said member when said frame is in another position; holding means carried by said frame and arranged to cooperate with said member to hold said frame in such other position; and means for locking said holding means in holding position.

7. In combination with a roofing bracket having a plank supporting member arranged to receive a plurality of hooks, a shoulder for engaging the edge of such plank and comprising: a frame having hooks adapted to be received by said member when said frame is in one position and to be locked to said member when said frame is in another position; and a link pivoted to said frame, cooperating with said member, and arranged to form with said frame an overthrow linkage adapted when set to hold said frame in such other position.

8. In combination with a roofing bracket having a plank supporting member arranged to receive a plurality of hooks, a shoulder for engaging the edge of such

- plank and comprising: a frame having hooks adapted to be received by said member when said frame is inclined to said member and to be locked to said member when said frame is perpendicular to said member; holding means adapted to hold said frame in such perpendicular position; and means for locking said holding means in holding position.
9. In combination with a roofing bracket having a plank supporting member arranged to receive a plurality of hooks, a shoulder for engaging the edge of such plank and comprising: a frame having hooks adapted to be received by said member when said frame is in one position and to be locked to said member when said frame is in another position; holding means adapted to hold said frame in such other position; and means for locking said holding means in holding position.
10. In combination with a roofing bracket having a plank supporting member arranged to receive a plurality of hooks, a shoulder for engaging the edge of such plank and comprising: a frame having hooks adapted to be received by said member when said frame is inclined to said member and to be locked to said member when said frame is
- perpendicular to said member; and means adapted to hold said frame in such perpendicular position.
11. In combination with a roofing bracket having a plank supporting member arranged to receive a plurality of hooks, a shoulder for engaging the edge of such plank and comprising: a frame having hooks adapted to be received by said member when said frame is in one position and to be locked to said member when said frame is in another position; and means carried by said frame and arranged to cooperate with said member to hold said frame in such other position.
12. In combination with a roofing bracket having a plank supporting member arranged to receive a plurality of hooks, a shoulder for engaging the edge of such plank and comprising: a frame having hooks adapted to be received by said member when said frame is in one position and to be locked to said member when said frame is in another position; and means adapted to hold said frame in such other position.

In testimony whereof, I hereunto affix my signature.

JACOB F. KEMMERLING.
